FIG. 1 is a top, front, and left side perspective view of a
portable article carrier showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The surface shading illustrated in the drawings is provided
merely to highlight the contour of the design; it is not intended
to be illustrative of texture or surface ornamentation. The
broken lines in FIGS. 1–7 illustrate portions of the portable
article carrier that form no part of the claimed design. The
broken away and bracketed portions in FIGS. 1–5 indicate that
no particular length is claimed for those portions; such lines
and any portion of the article between such lines form no part
of the claimed design.**1 Claim, 4 Drawing Sheets**(56)
